HANDLE FOR HAND TOOLS

Samuel D. Han, Leonia, N.J., assignor to Red Devil Inc.,
Union, N.J., a corporation of New Jersey

Filed Apr. 14, 1966, Ser. No. 1,896

Term of patent 14 years

(Cl. D93—4)

Both sides and both faces of the handle for hand tools are identical in appearance.

The broken lines are shown for illustrative purposes only.

I claim:

The ornamental design for a handle for hand tools, substantially as shown and described.
